W. DORNIG

HIGH FREQUENCY TRANSFORMER

Filed Dec. 2, 1921

WALTER DORNIG

BY HIS ATTORNEY

A. Parker Smith

UNITED STATES PATENT OFFICE.

WALTER DORNING, OF BERLIN-STEGLITZ, GERMANY.

HIGH-FREQUENCY TRANSFORMER.

Application filed December 2, 1921, Serial No. 519,325, and in Germany December 13, 1920.

The invention relates to high frequency transformers such as used for wireless telegraphy and is more especially directed to the improvement of the efficiency of frequency transformers by avoiding secondary currents of higher frequency in the primary circuits thereof.

Suggested by the frequency doubling process of Epstein and Joly-Vallaury, attempts have been already made to select the harmonics, especially the uneven ones, by the employment of iron cored transformers. With doubling processes employing continuous current saturated iron cores, as is well known, two separated iron cores or paths for the lines of force are necessary on which, when there are continuous current windings and secondary windings wound in the same direction, the primary currents are connected in the opposite direction. Consequently the ensuing secondary voltage of doubled frequency will not react on the primary circuit, only the difference between the two cores being effective.

By the adoption of any other principle of frequency multiplication by transformers, with or without continuous current magnetization, the direction of winding of the primary and of secondary is the same, so also the voltage of the secondary frequency corresponding to the transformation ratio of the transformer obtains on the primary terminals and permits a current to flow through the primary circuit in accordance with the resistance. It is preferred, however, for different reasons, for example, in order to obtain as flat a resonance curve as possible and a low voltage or to avoid the cost of induction coils, to use in the individual resonance circuits as high capacities as possible without self induction coils, except possibly, only a small variometer in order to bridge over the condenser unit. This causes very nearly a short circuit for the voltage of the secondary frequency under circumstances opposed to the resistance of the working circuit or, at least, a parallel connected circuit of few ohms. This is the cause of the bad efficiency of frequency multiplying systems. It has heretofore been proposed to provide in the primary circuit a so-called frequency trap to prevent a reaction of the secondary frequency on the primary circuit. This method is, however, objectionable since then whenever the secondary frequency is changed, the frequency trap must also be tuned to the new frequency. This is very disadvantageous, especially for a sender which has to send out waves of different frequency, as with each new wave the frequency trap then must be adjusted afresh.

According to the present invention choking coils are connected in the primary circuit which coils may be used also for tuning but they are of such size that the impedance of the primary circuit to the voltage of higher frequency amounts to a resistance which in relation to the working circuit is at least double.

By these means it is possible to design the choking coil so that it gives a highly protecting resistance for all secondary frequencies in question, and so that even if the secondary frequency is changed the primary circuit remains constant for all wave lengths.

The drawing shows by way of example an electrical diagram of the system according to the invention.

In the drawings, 1 is the oscillation producer, 2 and 4 are the tuning condensers, 5 is a self induction for protecting the secondary frequency, 6 is a frequency transformer, 7 and 8 are tuning elements for the secondary frequency, 9 the desired coupling with the antenna.

What I do claim as my invention and desire to secure by Letters Patent of the United States is:—

In an arrangement of the kind described, an alternating current generator, a frequency transformer, a primary circuit connected between the generator and the transformer, a wave radiator, a secondary circuit connected between the transformer and the wave radiator, a choking coil in the primary circuit with a resistance for the secondary frequency at least twice that of the wave radiator, a capacity in the primary circuit for tuning the same to the fundamental frequency, and a capacity in the secondary circuit for tuning the same to any desired frequency in the wave radiator.

In testimony whereof I affix my signature.

WALTER DORNING. [L. s.]
